(57) **CLAIM**

The ornamental design for a medical bag as shown and described.

DESCRIPTION

FIG. 1 is a front view of a medical bag showing my new design; the rear view is a mirror image of the front view; FIG. 2 is a right side view thereof; the left side view is a mirror image of the right side view;

FIG. 3 is a top plan view thereof;

FIG. 4 is a bottom plan view thereof;

FIG. 5 is a perspective view thereof; and,

FIG. 6 is a cross-sectional view thereof taken in the direction of line 6-6 in FIG. 3.

The broken lines depict portions of the medical bag that form no part of the claim.

1 Claim, 3 Drawing Sheets
